MACHINE FOR DRIVING RAIL FASTENING SCREWS IN RAILROAD TIES

William E. Piper, Salt Lake City, Utah

Application December 4, 1946, Serial No. 713,994

3 Claims. (Cl. 144—3)

1

This invention relates to a method of and machine for driving rail fastening screws in railroad ties although not necessarily limited to this purpose.

Among the principal objects of the invention are:

(a) To make feasible in railroad track construction the superior holding properties of screws over and above the usual track spikes, thus greatly promoting safety of travel.

(b) To provide portable means capable of expeditiously driving screws for fastening rails to ties.

(c) To prolong the life of wooden railroad ties.

(d) To effect worthwhile savings in the maintenance of railroad tracks.

Other important objects will become evident as the following description proceeds.

In spite of many attempts to improve upon the primitive wooden tie for supporting the steel rails of a railroad track, the fact remains that in the most modern track construction the wooden tie still holds practically first place.

An outstanding shortcoming in the use of wooden ties is the common method of fastening the rails to the ties by means of steel spikes that are driven into the ties. It is well known in the art of construction that the holding power of helically threaded screws is far greater than that of nails or spikes of approximately equal cross-sections.

The chief problem for using screws for fastening railroad rails to the ties heretofore has been the lack of facilities to drive lag screws in an expeditious and economical manner. The solution of this problem is accomplished by means of the invention.

In the method of the invention, specially designed lag screws are used instead of the usual track spikes for fastening the rails to the ties. A feature of the invention is to expedite the installation of the lag screws in the ties. Inasmuch as pilot holes must be drilled for lag screws, the method of the invention contemplates arranging a group of pilot drills in conjunction with a group of screwdrivers in order that the drilling of the pilot holes and the driving of the screws proceeds continuously and in the proper sequence. For this purpose pilot drills and screwdrivers are arranged in tandem so that while one set of holes is being drilled, another set of previously drilled holes is receiving the screws.

The placing of the screws is intended to follow substantially the usual plan of placing track spikes, that is to say, one screw is placed on each

2

side of the flange of the rail in each tie, the screws being spaced apart longitudinally along the rail or across the tie, so that the pattern in the aggregate presents a staggered configuration of the screws, corresponding to the usual staggering of track spikes.

In the machine of the invention, two groups of tools, drills or augers and screwdrivers, are advantageously mounted on a portable truck adapted to run on a railroad track. In the preferred form the truck is automotive in character, and is provided with a prime mover, such as an internal combustion engine, together with usual appurtenances such as transmission gearing, brakes and so on. Facilities for producing compressed air and electricity for use in operating the aforementioned tools can also be part of the portable truck plant.

In using the machine the truck is moved along a railroad track from one location to another, as required by any particular arrangement of the ties. As a rule, after the truck is "spotted" it is secured in place by any suitable means, such as a brake. In any principal spotted position the machine is disposed so as to operate simultaneously on two consecutive ties, that is to say, drilling four holes in one tie in order that two staggered holes straddle the flange of each rail. At each setting of the machine four screws are installed in the next preceding tie previously drilled. Therefore at each setting of the machine it operatively encompasses two ties. However, since railroad ties are seldom accurately spaced apart from each other, the method includes the step of expeditiously adjusting the tandem relative positions of the respective drills and screw drivers to suit the spacing of any particular ties.

In the accompanying drawings, which illustrate one embodiment of a machine according to the invention,

Fig. 1 represents a general plan of the machine arranged in the form of a truck, the platform being omitted so as to reveal the substructure.

Fig. 2, a fragmentary side elevation corresponding to Fig. 1, parts in the background being omitted;

Fig. 3, a vertical section taken on the line 3—3 in Fig. 2;

Fig. 4, a fragmentary portion enclosed by the line 4 in Fig. 1, but drawn to an enlarged scale;

Fig. 5, a fragmentary plan showing a group of screws as they appear in the finished track;

Fig. 6, an elevation in the direction of arrow 6 in Fig. 4, or an enlargement of substantially the elevation shown in Fig. 2, certain portions being

broken away for convenience; in this figure the drills and the screwdrivers are shown in alternative positions relatively to Fig. 2;

Fig. 7, a vertical section taken on the line 7—7 in Fig. 6;

Fig. 8, a vertical section showing an alternative construction adapted for use with the machine of the invention;

Fig. 9, an elevation, partly in section, of a special lag screw adapted for use with the machine of the invention;

Fig. 10, a top plan corresponding to Fig. 9;

Fig. 11, a fragmentary vertical section taken on the line 11—11 in Fig. 4, drawn to an enlarged scale, portions being omitted for convenience;

Fig. 12, a fragmentary vertical section taken on the line 12—12 in Fig. 4, drawn to an enlarged scale, portions omitted;

Fig. 13, a diagram, in detailed vertical section, of a tool lifting mechanism;

Figs. 14 and 15, an axial section taken through the operating valve of Fig. 13, drawn to an enlarged scale;

Fig. 16, a plan in outline, of the entire machine; and,

Fig. 17, an electric wiring diagram.

Referring to the drawing, the numeral 20 denotes the rails of a railroad track, while the numerals 21 to 24 denote ties on which the rails are supported. It is well known that a lag screw always requires a pilot hole to be drilled or bored in wood before driving the screw, the hole being somewhat less in diameter than the screw. The tools used are drill or auger bits and screwdriver bits, which in the present instance are inserted in suitable chucks and rotated electrically in a manner that is well known. Chucks, in Fig. 6, otherwise in Fig. 2.

Assuming that the machine 30 of the invention is spotted as shown in Fig. 1, and further, that the screws 25 have previously been driven in certain ties 21, and assuming also, Fig. 2, pilot holes 22a in tie 22 have just been drilled, it brings the observer to the point where screws 25a are held by the respective screwdriver bits 27 ready for driving into the holes 22a in tie 22. At the same time drill bits 26 are ready to be plunged into tie 23. After driving screws 25a and drilling pilot holes in tie 23, the machine will be ready for moving to the next position (not shown).

At each spotting of the machine, four holes are drilled and four screws are driven. Obviously this requires four drilling units and four screw-driving units, the electric motor rotating means 28 being advantageously of the same kind and purchasable in the open market. A special feature of each rotating means 28 is an elongated sleeve 29 for reinforcing the stems that hold the respective drill bits 26 and screwdriver bits 27. Hereinafter the drilling units in general will be termed simply "drills" and the screwdriver units "screwdrivers."

The drills straddle a rail in pairs, and likewise the screwdrivers, it being understood that the relative spacing is the same, since the screwdrivers must be in alignment with the holes previously drilled.

In the present showing the machine 30 comprises a platform 31 mounted on a substructure or running gear 32, which in turn is mounted on axles 33 having flanged wheels 34. The running gear in this instance includes the side frames 35 which are advantageously made up of forked beams 36 and depending beams 37,

these being structural steel channels suitably united by welding or otherwise. The side frames 35 rest on journal boxes 38 in which the axles 33 are rotatable, all in accordance with general practice, the present showing being merely illustrative. The two side frames are connected to each other transversely by beams 39 and 40.

Fixed on top of the depending beams 36, for instance by spot welding, are guide channels 41, 10 and spaced apart from these and directly above are similar but inverted guide channels 42, the latter being supported on the uprights 43. Disposed for reciprocation in guide channels 41 and 15 42 are the respective pairs of long slides 45, 46, and short slides 45—1, 46—1, Figs. 4 and 6. Fixed on slides 45 and 45—1 are bosses 47, and on slides 46 and 46—1, bosses 48. Rigidly mounted in bosses 47 are standards 49, and in bosses 48 are standards 50. Near the top of each of the standards 49 and 50 are air-lift cylinders 51, these being clamped in the respective bands 52 by means of set screws 53. The hub portions 54 of the bands are in turn fixed on the respective standards. Below the air-lift cylinders 51 are 20 the electric rotating units 28, these being held in bands 55 having hub portions slidable on standards 49 and 50. Thus are formed two pairs of intersliding tool carriages above each rail, the carriages being manipulated as will presently be described.

The purpose of the air-lifts 51 is to move the respective electric units up and down as required for pushing a pilot drill into a tie, pulling it out again, and similarly driving a screw into a tie 35 and again retracting the screwdriver. As in any air-lift, a piston 57, Fig. 13, is mounted on a piston rod 58. For the present purpose, each piston rod at its lower end is fixed in a hub 59 forming an integral part of each respective electric unit 28. In Fig. 2, the piston and the parts attached to it are shown in an upper position, while in Fig. 3, the same parts are shown in a lower position.

In using the machine, it is spotted approximately above a pair of ties and secured in place by any means, such as a vehicle brake (not shown). The tool carriages are then individually spotted according to the desired placing of the novel track screws 25. As at present shown, the machine moves progressively towards the right as indicated by the arrow 44 in Fig. 4. Therefore, the tool duality at the right of this figure consists of drills and that at the left, of screwdrivers. In the event of moving the machine progressively counter to the arrow 44, it only means interchanging the different bits 26 and 27.

The mechanism for individually spotting the tools comprises for illustration lever arm 60, Figs. 4 and 11, having a pin 61 working in a slot 62 formed in the end of the slide 46. Another arm 63, the counterpart of 60, is similarly pivoted to the slide 46—1. The arms 60 and 63 are rigidly mounted on a quill or tubular shaft 64. The arm 69 has a lug 65 in which is hooked the rod 66 that is connected to the lower end of an operating lever 67. By moving the operating lever back and forth corresponding movement is transmitted through the various connecting parts to the carriage of slides 46 and 46—1. In a similar manner, the carriage of slides 45 and 45—1 is moved back or forth by means of the arms 68 and 69 that are rigidly mounted on a shaft 70 that works inside the quill 64. The arm 68, lug 71, rod 72, and operating lever 73 are similar to 70 75 the corresponding parts just previously described.

Each operating lever works on a pivot fixed in the respective bracket 75, the latter being mounted on the crossbeam 39. Each bracket has a quadrant 76 with a friction face 77 engaged by a friction shoe 78 under normal pressure of a compression spring 79. When desired, the friction shoe can be released from contact with face 77 by means of a grip 80 connected to a rod 81 that in turn is attached to the shoe 78. The respective tools are thus maintained against displacement during operation of the tools. What has just been explained applies as well to the tools shown on the far side of the center line C—C, Fig. 1, with the exception that the parts are reversed.

In Fig. 8 an alternative of the tool-carrying slides is shown. In this construction the slides 84 and 85, instead of being completely rectangular, are provided with shoe strips 86 that reduce the frictional bearing areas between the slides themselves and between the slides and their guide channels.

A convenient way of operating the various drills and screwdrivers is by means of electric push button controls as illustrated in the wiring diagram, Fig. 17. Two operators are required one at the control station A for the nearside tools and the other at the station B for the farside tools. In addition, two service persons are stationed within the manhole 87, Fig. 16, the duties of these servicers being principally to supply screws to the screwdrivers from a stock carried on board the car, and to perform any other needed service.

Assuming that the various control means are within convenient reach of the operators, the car is spotted in a position where the tools are poised above a pair of ties somewhat as indicated in Fig. 2, leaving the tools ready to descend and to perform their respective functions. In the present instance the descent of the tools is brought about by gravity, it being assumed that the electric units 28 and the various appurtenances suspended from the piston rods 58 have sufficient weight to supply the pressure necessary for pushing the drills 26 into the tie as well as to bear down sufficiently on the screwdrivers to cause the screws to be driven into the previously drilled pilot holes. The screws before being driven are removably held by the screwdriver bits in any one of several different ways so that after the driving is completed, the bit can be easily withdrawn from the screw. In the present instance the bits 27 are assumed to be Alnico permanent magnets, square in cross-section, so that the service men need only place the screws 25 on the magnetic bits in the proper position, Fig. 9.

The wiring diagram, Fig. 17, sets forth the working of the system. In the normal status a solenoid 88 in a circuit 89 is under energization to hold a three-way valve 90 in the position of Fig. 14, where it admits compressed air to the cylinder 51 from a suitable source (not shown) by means of a conduit 90—1, holding, the piston 57 at the upper end of its stroke. Circuit 89 is controlled through a relay solenoid 91 that is under energization counter to the tension of a spring 92 that holds double switch 93 closed. Normally, the motor 28—1 that includes a limit switch 28—2, is dead.

To start a tool on the working course, the operator presses a push-button 94, thereby deenergizing relay 91 and in turn, solenoid 88. This causes the evacuation of the air from cylinder 51, and consequently, the descent of piston 57 with its load hanging on piston rod 58. Before the

tool strikes, a push-button 95 is pressed momentarily; this energizes a relay solenoid 96 and closes a double switch 97 that energizes a motor circuit 98, causing motor 28—1 and its corresponding tool to rotate. Rotation of the motor continues after push-button 95 is released because of the holding contact of relay 96. As soon as the descending tool reaches the desired point, limit switch 28—2 contacts a point 99 on the flange of a rail and moves switch element 100 counter to the tension of a spring 101. This energizes relay conductor leg 102 momentarily, and through relay 91 restores the starting status through solenoid 88, meanwhile having deenergized relay conductor leg 103 whereby the holding contact of solenoid 96 is released, thus restoring the entire circuit to its normal status. This concludes an operation cycle of one particular tool 28 and leaves it ready for the next cycle. For stopping the motor in emergencies a push-button is located at 104.

Wiring, as just described, is provided for each tool, which means four sets or twelve buttons on each of the control panels 105 and 105—1 in Fig. 16.

It will be understood that during the down stroke of a tool, the valve 90 will be in the position of Fig. 15, causing the air under piston 57 to be discharged through passage 106, a regulating valve 107 being pre-set to prevent too rapid a drop. At 108 is a regulating valve pre-set against excessive upstroke speed.

In order to take care of the proper spacing of the dual drills or dual screwdrivers, Fig. 4, transversely of a rail as demanded by variations in width of rail flanges, the hereinbefore mentioned set screws 53 can be loosened, thereby leaving the affected tool free for turning about its axis 109. Since such electric tools customarily have the axis 110 of the bit eccentric relatively to the axis 109, the tool is turned about the latter axis until the desired spacing of the bit axis is attained. Thereupon, set screw 53 is tightened for the new position.

Attention is directed to the importance of so supporting the duality of tools that their accessibility is not impaired in being serviced. To this end the depending beam 36, which occupies only the limited space between the two opposite edges of a rail flange, is well adapted. Thus, the tool stems carrying the bits are allowed to straddle the rail, leaving at the same time sufficient man-hole clearance on each side thereof, as clearly shown in Fig. 16.

In the broad aspect of the invention other means than those herein described can be resorted to for lifting and lowering the tools and for rotating them, as will be obvious to those skilled in the art.

In some cases it might be desirable to provide a magnetic or other type of yielding clutch, as is well known, to hold a screwdriver bit in a way to avoid excessive torque stresses, especially when a screw is driven home to bear on top of the rail flange. In Fig. 9 it is to be noticed that the frusto-conical surface under the head of the screw 25 conforms to the customary 13 degree angle of a standard rail flange.

In the present drawings the spacing of the ties is shown as being uniform, but in actual practice considerable variation occurs, especially on curves. Therefore, after roughly spotting the machine over a pair of ties, the final spotting of the individual carriage-supported tool dualities is expeditiously accomplished by means of levers

67 and 73 working through the respective connections.

In specifying the locations of the various tools, it is convenient to refer to the two that are in conjunction over the same rail and the same tie as a "duality." For example in Fig. 2, a duality of drills is enclosed by the broken loop 111, and a duality of screwdrivers by the broken loop at 112. Thus, it will be clear that there is a pair of drill dualities spaced apart from each other lengthwise of a tie, and similarly a pair of screwdriver dualities spaced apart from each other lengthwise of the next tie, the pairs of said dualities being in tandem arrangement lengthwise of the track.

Whereas this invention has been described with respect to a preferred specific embodiment thereof, it should be understood that various changes may be made in said embodiment and various other forms of the invention may be constructed by those skilled in the art without departing from the general purview of the following claims.

I claim:

1. In a railroad work car for driving rail-holding screw spikes, a substantially rectangular, substantially centrally-disposed manhole having a width comprehending the rail span and a length at least sufficient to comprehend two successive ties; transversely spaced beams within and extending longitudinally of said manhole in positions immediately above the respective rails; a rectangular frame resting on said beams and rising vertically from said manhole; forward and rearward pairs of longitudinally spaced standards mounted for respectively independent longitudinal sliding movement in said frame at opposite sides thereof; pairs of rotary tools eccentrically mounted for vertical sliding movement on respective pairs of standards, the component tools of each pair extending at opposite sides of the beam above which they are mounted; means for adjustably moving the respective pairs of standards relative to one another; means for rotating the respective tools; and means for lower-

ing and raising the respective tools on said standards.

2. The combination recited in claim 1, where-in the means for rotating the respective tools are respectively independent electric motors which serve to eccentrically mount said tools on the standards; and the means for lowering and raising the respective tools are air-operated piston and cylinder assemblies fixed eccentrically on said standards and coupled to the respective electric motors for lowering and raising said electric motors and the tool holders which carry.

3. The combination recited in claim 2, where-in the upper and lower longitudinal members of the frame constitute slideways, and the pairs of standards are fixed to upper and lower slides slidably engaging respective upper and lower slideways.

WILLIAM E. PIPER.
